US00D717304S

(12) **United States Design Patent**
Yturrealde et al.

(10) **Patent No.:** **US D717,304 S**
(45) **Date of Patent:** **** Nov. 11, 2014**

(54) **SCANNING JACKET FOR A HANDHELD DEVICE**

(75) Inventors: **Mark C. Yturrealde**, San Diego, CA (US); **Reza A. Ghanbari**, San Diego, CA (US)

(73) Assignee: **PatientSafe Solutions, Inc.**, San Diego, CA (US)

(**) Term: **14 Years**

(21) Appl. No.: **29/416,709**

(22) Filed: **Mar. 26, 2012**

(51) **LOC (10) Cl.** **14-02**

(52) **U.S. Cl.**

USPC **D14/420**; D14/250; D14/440

(57) **CLAIM**

We claim the ornamental design for a scanning jacket for a handheld device, as shown and described.

DESCRIPTION

FIG. 1 is a perspective view of a scanning jacket for a handheld device configured in accordance with the present invention;

FIG. 2 is a top view thereof;

FIG. 3 is a bottom view thereof;

FIG. 4 is a right side view thereof;

FIG. 5 is a left side view thereof;

FIG. 6 is a rear view thereof; and,

FIG. 7 is a front view thereof.

Broken lines and unshaded portions contained within broken lines are not claimed.

1 Claim, 5 Drawing Sheets
